UNITED STATES PATENT OFFICE

JOHN D. HASKELL, OF FULTON, NEW YORK, ASSIGNOR TO DILTS MACHINE WORKS, INC., OF FULTON, NEW YORK, A CORPORATION OF NEW YORK

PULP BEATER, EXTRACTOR, AND CLEANER

Application filed November 5, 1929. Serial No. 405,031.

This invention relates to pulp beaters, extractors and cleaners and belongs particularly to unit machines for kindred purposes in the manufacture of paper.

3 An object of this invention is to construct as a unit not only a breaker beater, but also a settling trough and thickener, which will eliminate the elaborate systems such as are disclosed in certain patents of the United States. In other words it is an object of this invention to accomplish the same result in a single unit machine as is now ordinarily attained by a series of individual units connected together. In some apparatus of the 18 nature herein mentioned the settling troughs are one hundred to one hundred and fifty feet in length. The reason for making such troughs of that length, apparently extreme, is that when the beater is started up, say Monday morning, and the stock diluted to about one-half of one per cent to allow the heavy particles and materials such as sand, dirt and even paper clips and the like to settle out, the first ten feet of the settling trough 25 collects substantially most of such foreign matter. After a run of about one day this first ten feet of the trough is completely filled with this dirt, sludge and the like so that the stock coming into the trough simply 30 passes over that accumulation and settles out further down the trough. By the end of the week's run practically no dirt is settled out in the first few feet of the trough, and baffles are introduced at the extreme end of the 35 trough to collect such unsettled materials.

By the construction and arrangement of parts as shown in this invention it is sought to provide an arrangement of baffles or sand settling compartments provided with receptacles the bottom portions of which taper downwardly as set forth, and are furnished with removable bottoms of any selected formation and operation. Normally the bottoms of the receptacles are open, the closures 40 having been removed, and in this way the first few sand boxes collect usually the greater amount of refuse, which settles down through the open bottoms of the receptacles into the compartment below. As this heavier material 45 settles it displaces the lighter stock and

water and eventually fills the compartments below the sand receptacles. When this condition of settlement is reached, the removable bottom of the receptacle or receptacles is reseated to close the open bottom, and the compartment below is then accessible for cleaning out the refuse collected in the compartment without shutting the machine down, as the diluted stock will simply by-pass the compartment which is being cleaned out. It is a 55 further object of this invention to equip each compartment with an easily removed or opened and closed watertight door, so that the operation of cleaning out the compartment may be accomplished as quickly as 60 practicable. Only one of the compartments need be cut out of service at any one time. It is intended that if necessary this cleaning procedure may be undertaken once or twice 65 a day, and in this manner the undesirable extreme length of the settling trough can be 70 obviated successfully.

It is also an object of this invention to combine as herein shown and described a long wire net covered cylinder mould similar to 75 standard wet machine types for thickening the dilute stock, all of which can be built into the single unit machine. A pump is shown in this application and adapted for drawing off the water from the inside of the cylinder 80 mould and returning the so-called "white water" back to the mixing chamber or into the beater tub where desired. The thickened stock leaves the mould by way of a couch roll from which it is scraped off and dis- 85 charged to a chest or to other refining equipment the same as is the common practice with wet machines.

The special construction and arrangement 90 of the various parts of the unit machine comprising this invention are illustrated in the accompanying drawings, of which Fig. 1 represents a side view partly in vertical section, and showing all parts assembled. Fig. 2 is a vertical cross section of one of the settling 95 compartments, and the tapering receptacle therein showing the removable bottom of the receptacle, and the hook rod ordinarily employed to take the bottom out and to replace it. Fig. 3 is a vertical cross section of part 100

of the mixing chamber showing the vertically extending director plate which is located in proximity to the beater roll, and illustrating also the gears, gear shaft and handwheel for moving the adjustable gate or slide of the director plate. Fig. 4 is a top view of the parts set out in Fig. 1. Fig. 5 is a fragmentary vertical and longitudinal section transversely of the beater roll shaft, showing perforations in the up curve of the director plate, and setting out likewise a perforated beater plate beneath the beater roll covering a chamber opening into the mixing chamber. Fig. 6 is a fragmentary top view showing a screen arranged at the curve of the inner wall of the tub. Fig. 7 is a fragmentary vertical section to show the breaker roll provided with an extractor hood to receive pulp thrown off by the breaker roll of sufficient fineness to pass the perforations. In Fig. 7 also is shown the slice partition exhibiting the openings or recesses therein and the plates for controlling the extent of the open recesses in practice. In Fig. 7 is set forth also a representation of the pipe for conducting material from the breaker roll extractor hood into the tub near the beater roll. Fig. 8 is a top view of the parts shown in Fig. 7, with the hood extractor chamber shown in section. The pipe for conducting the fluent material from the extractor hood to the tub next to the beater roll is also illustrated in Fig. 8. Fig. 9 is an end portion of the movable part of the slice partition, and sets out the adjustable plates which are used to control the size of the recesses in the plates, and the clamps for securing the plates are indicated. Fig. 10 is a side view partly sectional showing a bladed auxiliary roll to take beaten stock from the beater roll.

Throughout the drawings and description the same number is used to refer to the same part.

Considering the drawings, upon a suitable base 1 the tub 2 is erected and provided with a midfeather 3 of any chosen form and extent. A roll shaft 4 carries a beater roll 5 and a breaker roll 6, the beater roll being of larger diameter than the breaker roll. Ordinarily a hood 7 covers the rolls, and the rolls are combined in one as set forth. The breaker roll may be of standard construction with approximately twenty flybars, whereas the beater roll would be of larger diameter with a greater number of bars spaced closer together, since it is not necessary to produce circulation by the beater roll. In proximity to the beater roll is an upwardly curving and extending plate, termed for the purposes of this description a director plate, since it directs the beaten stock upwardly to the opening 10 controlled by the sliding gate 11 actuated by suitable racks and gears 12 on cross shaft 13, revolved by handwheel 14, as best shown in Fig. 3. The construction and

disposition of the plate 9 is such that the applicant is enabled to dispense entirely with any screen or perforated plate or plates. It will be noted that the opening 10 controlled as described is well up in plate 9, and the idea of this arrangement is in practice to hold back a considerable quantity of the stock in the beater roll chamber by means of the adjustable opening marked 10, and only permit enough stock to pass into the mixing chamber adjoining the plate 9 as would be required for the set production from the machine. The rest of the stock would continue over the roll and under the roll upon the bed plate for further treatment. As shown in Figs. 1 and 5 a doctor 15 directs the material thrown off by the beater roll through the opening 10. It is believed to be within the purview of this invention to use any construction of doctor device.

As delineated in Figs. 1, 4, 7 and 8 this invention includes a slice partition made up of a lower and fixed part 16, and an upper part 17 movable with respect to the lower part, by means of the adjusting screws 18 and handwheel nuts 19 supported by the cross bars 20. As best illustrated in Figs. 7 and 9, the upper and movable part 17 of the slice partition has a number of openings 21, and the sizes of the openings are governed by the sliding plates 22 secured by clamps or screw buttons 23. This invention is in no sense limited to the plates and the clamps for adjusting the open area of any recess 21, as those devices are susceptible of various modification.

In Figs. 4 and 8 is shown an ordinary backfall in proximity to the breaker roll 6.

Considering Figs. 1 and 4 there will be noted next the upwardly extending plate 9 a mixing chamber 25, into which the material from the beater roll is directly diverted, and the side of the chamber 25 opposite the plate 9 is constituted by the vertical baffle plate 26, of which there are a succession as set forth. The tops of the baffle plates 26 are below the top edge of the tub, and from the top of the tub walls intermediate baffle plates 27 extend downwardly. The baffle plates 26 and the outer wall of the tub with its inner wall 2' comprise a series of compartments of which any number may be provided. In each compartment is a refuse receptacle 28 the sides of which taper downwardly, and each receptacle has an open bottom which may be closed by a removable bottom plate 29, as best illustrated in Fig. 2, and the closure 29 is usually manipulated by means of a hook rod 30 which is engaged and disengaged with a pin 31 carried by the closure 29 in a small recess as set out. The compartments formed by the baffle plates or partitions 26 and the walls of the tub, are provided externally at the bottom as illustrated in Fig. 120

1 with suitable watertight clean-out doors 32, having latching devices 33. Further considering Fig. 1, it will be seen that the last compartment 34 of the series of settling compartments discharges through a vertical wall 35 having one or more openings 36, into a chamber 37, best shown in Fig. 4. In the chamber 37 a wire screened roll 38 revolves, and in contact with the roll 10 is a couch or take-off roll 39 adapted to take the thickened stock off the screen roll 38. The roll 39 is scraped by the doctor blade 40, and the thickened and cleaned stock is deposited in the final chamber 41, shown in Fig. 15 4, from which chamber by way of the outlet pipe 42 the stock may be conducted to a chest or further refining machinery not shown. To wash off the screen roll 38 externally, the spray head 43 of any desired 20 construction and arrangement is introduced as shown in Fig. 1. It will be noted further in Fig. 1 that a connection 44 is in communication with the interior of the screen roll 38, and by way of connection 44 the rotary 25 pump 45 takes the water from the interior of the roll and forces the same past valve 46 through the elevated pipe 47 into the mixing chamber 25, or elsewhere into the tub as may be desired. Obviously, the flow of returned 30 water in pipe 47 may be divided and delivered at any points found to be advantageous in a given operation.

It is further believed to be within the scope of this invention to replace the relatively 25 wide bed plate 8 set forth in Fig. 1 by a perforated bed plate 49 adapted to pass beaten stock downwardly into a receiving box 50, which is in open communication with the mixing chamber 25. It is believed to be 40 equally the right of this applicant to provide the inner wall 2' of the tub at the turn of the wall as shown in Fig. 6, with a screen 51 for the passage of stock suitably beaten. The curving and up-turning portion of the 45 director plate 9 near the roll 5 may be provided with a perforated portion 48 for passing beaten stock into the mixing chamber 25. Such additions are held by this applicant to be minor details, as they are devices of well 50 known structure and their operation and use is common knowledge in the industry to which this invention is designed to be applied.

Considering Fig. 7 there will be noted adjacent to the beater roll 5 an adjustable doctor blade 52, which can be changed in position either to the right or left or up or down as may be chosen. There may be also applied to the breaker roll 6 as set forth, an extractor hood 53 having a perforated face plate 54, and an internal spray pipe 55 to clean the perforated plate by water spray. From the lower part of the hood 53, pipe 56 conducts the fluent matter into the space between

the slice partition 16 and the beater roll as set out also in Fig. 8.

Considering Fig. 10, there will be noted in the place of the doctor blade, an auxiliary roll 57 on a cross shaft 58 whereby it may be rotated by means not shown but of any common elements, near the beater roll 5 and in like direction. The blades 59 of the auxiliary roll in passing near the blades of the beater roll take the material from the beater roll 75 and throw the same against and through the curved screen 60 swept by blades 59 of the auxiliary roll and the screen is kept clear by the movement of those blades. Such portions of the material not passed through the 80 screen 60 are carried by the beater roll over the top thereof and under the hood 7 to be again passed under the beater roll. It will be observed in Fig. 10 that the curved screen 60 is removably secured to the director plate 85 9 by the bolts 61. Any desired changing of the screen may thus be made.

In the operation of this invention, the stock beaten by the beater roll passes into the mixing chamber and into one after the other of the settling compartments described. The refuse materials are deposited in those compartments as previously explained, and they are cleaned out one at a time if need be and without interfering with the continuous running of the apparatus for any length of time. The cleaned and thickened stock is taken out at the end of the series of settling compartments, and the water therefrom returned to the mixing chamber or tub. 100

The heavier materials are broken up by the breaker roll, and the lighter portions in circulation pass between the slice partitions 16 and 17, or over the latter and through the different recesses 21 adjusted as required for 105 a given operation. Having now described this invention and the manner of its use, I claim:—

1. In pulp beating apparatus of the character described, the combination with a tub, 110 of a combined breaker and beater roll having the same shaft means whereby the breaker roll circulates the stock in the tub, a series of refuse receiving receptacles partitioned from the tub, and said beater roll being arranged to direct beaten stock into said receptacles. 115

2. In pulp beating apparatus of the character described, the combination with a tub, of a combined breaker and beater roll having the same shaft, means whereby the breaker roll circulates the stock in the tub, a series of refuse receiving receptacles partitioned from the tub, said beater roll being arranged to direct beaten stock into said receptacles, and stock thickening devices arranged at the end of 120 said series of receptacles. 125

3. In pulp beating apparatus of the character described, the combination with a tub, of a combined breaker and beater roll having 130

the same shaft, means whereby the breaker roll circulates the stock in the tub, a series of compartments provided with clean-out doors, and said beater roll being arranged to direct 5 beaten stock into said series of compartments.

4. In pulp beating apparatus of the character described, the combination with a tub, of a combined breaker and beater roll having the same shaft, means whereby the breaker roll 10 circulates the stock in the tub, a series of compartments each having a refuse receiving receptacle therein, means for dumping the refuse from the said receptacles into said compartments, and doors whereby the compartments 15 may be individually cleaned out.

5. In pulp beating apparatus of the character described, the combination with a tub, of a combined breaker and beater roll having the same shaft, means whereby the breaker roll 20 circulates the stock in the tub, a series of compartments each having a refuse receiving receptacle therein, each receptacle having a movable portion whereby the contents of the receptacle may be dumped into 25 the compartment, and each compartment having its lower portion provided with an opening and a watertight clean-out door upon the opening.

6. In pulp beating apparatus of the character described, the combination with a tub, of a combined breaker and beater roll having the same shaft, means whereby the breaker roll 30 circulates the stock in the tub, perforated walls located in proximity to said 35 combined roll and adapted to pass fiber bearing fluid thrown off by said roll, and means for returning into the tub adjacent to said beater roll fluid matter which has passed said perforated walls.

40 7. In pulp beating apparatus of the character described, the combination with a tub, of a combined breaker and beater roll having the same shaft, means whereby the breaker roll 45 circulates the stock in the tub, a mixing chamber, a vertically extending director plate arranged between the said mixing chamber and said beater roll and having an opening through which matter thrown off by 50 said beater roll may enter said mixing chamber, and settling compartments located and constructed to receive matter from said mixing chamber.

8. In a pulp beating apparatus of the character described, the combination with a tub, of a combined breaker and beater roll having the same shaft, means whereby the breaker roll 55 circulates the stock in the tub, a mixing chamber, a vertically extending director 60 plate located between said mixing chamber and said beater roll and having an opening through which matter thrown off by said beater roll may enter said mixing chamber, adjustable means for controlling the said 65 opening, and settling compartments ar-

ranged to receive matter from said mixing chamber.

9. In pulp beating apparatus of the character described, the combination with a tub, of a combined breaker and beater roll having 70 the same shaft, means whereby the breaker roll circulates the stock in the tub, a mixing chamber, a vertically extending director plate located between said mixing chamber and said beater roll and having an opening 75 through which matter thrown off by said beater roll may enter said mixing chamber, settling compartments arranged to receive matter from said mixing chamber, and means for returning fluid matter from one of said 80 compartments to said mixing chamber.

10. In pulp beating apparatus of the character described, the combination with a tub, of a combined breaker and beater roll having the same shaft, means whereby the breaker 85 roll circulates the stock in the tub, a mixing chamber, means for directing matter thrown off by said beater roll into said mixing chamber, settling compartments arranged to receive matter from said mixing chamber, and means for extracting thickened and cleaned 90 stock from the said settling compartments.

11. In pulp beating apparatus of the character described, the combination with a tub, of a combined breaker and beater roll, means 95 whereby the breaker roll circulates the stock in the tub, a mixing chamber, means for directing matter from the said beater roll into the mixing chamber, a slice partition arranged in the path of the stock circulated by 100 said breaker roll whereby the upper portion of the stock is allowed to pass to the beater roll and the lower portion to the breaker roll.

12. In pulp beating apparatus of the character described, the combination with a tub, of a combined breaker and beater roll, means whereby the breaker roll circulates the stock in the tub, a mixing chamber, means for directing matter from the said beater roll into 105 the mixing chamber, a movable slice partition arranged in the path of the stock circulated by said breaker roll whereby a portion of the stock is allowed to pass to the beater roll and a portion directed to the breaker roll, and means for positioning the 110 said slice partition.

13. In pulp beating apparatus of the character described, the combination with a tub, of a combined breaker and beater roll, means 120 whereby the breaker roll circulates the stock in the tub, a mixing chamber, means for directing matter from the said beater roll into said mixing chamber, a slice partition arranged in the path of the stock circulated by the said breaker roll, the said slice partition having a fixed portion and a movable portion whereby a portion of the stock is allowed to pass to said beater roll and a portion directed to said breaker roll, and means 125 130

for positioning the said movable portion of the said slice partition.

14. In pulp beating apparatus of the character described, the combination with a tub, of a combined breaker and beater roll, means whereby the breaker roll circulates the stock in the tub, a mixing chamber, means for directing matter from the said beater roll into said mixing chamber, a slice partition arranged in the path of the stock circulated by the said breaker roll, the said partition having openings therein whereby a portion of the circulating stock is allowed to pass to the beater roll and the remainder of the stock is directed by said partition to the breaker roll.

15. In pulp beating apparatus of the character described, the combination with a tub, of a combined breaker and beater roll, means whereby the breaker roll circulates the stock in the tub, a mixing chamber, means for directing matter from the said beater roll into said mixing chamber, a slice partition arranged in the path of the stock circulated by the said breaker roll, the said partition having a fixed lower part and a movable upper part, the said upper part of the partition being provided with openings, means for positioning the said movable part of said partition with respect to said lower part.

16. In pulp beating apparatus of the character described, the combination with a tub, of a combined breaker and beater roll, means whereby the breaker roll circulates the stock in the tub, a mixing chamber, a slice partition arranged in the path of the stock circulated by the said breaker roll, the said partition having openings therein, means for controlling the size of said openings, and means for directing matter from the said beater roll into the said mixing chamber.

17. In pulp beating apparatus of the character described, the combination with a tub, of a combined breaker and beater roll, means whereby the breaker roll circulates the stock in the tub, a mixing chamber adjoining the beater roll, settling compartments in communication with said mixing chamber, and means for dividing the stock circulated by said breaker roll whereby the lighter portion of the stock is directed to the beater roll and the heavier portion to the said breaker roll.

18. In pulp beating apparatus of the character described, the combination with a tub, of a combined breaker and beater roll, means whereby the breaker roll circulates the stock in the tub, a mixing chamber adjoining the beater roll, settling compartments in communication with said mixing chamber, said compartments having a common inner wall, said tub having a midfeather spaced from said wall whereby the stock circulated by said breaker roll passes between said wall and midfeather.

19. In pulp beating apparatus of the char-

acter described, the combination with a tub, of a combined breaker and beater roll, a mixing chamber adjoining the beater roll, settling compartments in communication with said mixing chamber, said chamber and compartments having a common inner wall, means extending upwardly in proximity to said beater roll for directing stock into said mixing chamber, the said directing means and the peripheral face of the beater roll being substantially of the same width as the said mixing chamber and said compartments.

20. In pulp beating apparatus of the character described, the combination with a tub, of a combined breaker and beater roll, means whereby the breaker roll circulates the stock in the tub, the said beater roll being of greater diameter than the breaker roll, and a slice partition arranged in the path of the stock circulated by the said breaker roll and extending in a slanting direction from the wall of the tub for the width of said beater roll whereby a portion of the stock flow is allowed to pass to said beater roll and the remainder of the stock is directed to said breaker roll.

In testimony whereof I affix my signature.
JOHN D. HASKELL.
